UNITED STATES PATENT OFFICE

ELMER DODDRIDGE, OF SOUTH BEND, INDIANA

SHOCK ABSORBER

Application filed January 27, 1928. Serial No. 249,919.

The invention relates to improvements in shock absorbers, and has for its object to provide a device of this character in which hydraulic means alone are used to absorb the shocks.

A further object is to provide a device of this character in which the springs ordinarily used in devices of this character are entirely dispensed with.

10 A further object is to provide a device of this character which is simple of construction, cheap to manufacture, and easy to assemble.

15 A further object is to provide a device of this character in which a plunger slidably mounted in a cylinder acts against an incompressible fluid, and in so acting provides a cushioning motion for the vehicle to which the device is attached.

20 A further object is to provide a device of this character having means whereby the action of the device may be regulated, as for hot and cold weather.

25 A further object is to provide a device of this character in which easy access may be had to the internal parts thereof to allow repairs to be made.

With the above and other objects in view, the invention resides in the combination and arrangement of parts as hereinafter set forth, 30 shown in the drawing, described and claimed, it being understood that changes in the precise embodiment of the invention may be made within the scope of what is claimed without departing from the spirit of the invention.

25 In the drawing:

Figure 1 is a vertical sectional view of the device.

40 Figure 2 is a transverse sectional view of the device taken on line 2—2 of Figure 1.

Figure 3 is a transverse sectional view of the device taken on line 3—3 of Figure 1.

Figure 4 is a vertical sectional view of the removable cylinder and the valves.

45 Figure 5 is a fragmentary view of the device showing the valve regulator and indicator.

Figure 6 is a fragmentary sectional view of the device showing the regulating valve.

50 Referring to the drawing, the numeral 1

designates the casing of the device which is preferably cast into shape. The casing 1 has no bottom, but the lower end thereof has internal threads 2, by means of which a closure member 3 is secured to the casing 1. The 55 closure member 3 is provided with an annular groove 4, which is adapted to receive a washer, thus making a tight connection between the closure member 3 and the casing 1 which will prevent leaking. Secured within the casing 1 by means of the threads 2 is a cylinder 5 having a threaded annular flange 6 at its lower end. The cylinder 5 is also provided at its upper end with a recessed bevelled flange 8, which abuts the bevelled annular shoulder 9 within the casing and thus insures a correct 60 positioning of the cylinder 5 in the casing 1. Within the cylinder 5 is disposed a tight fitting 65 slideable plunger 10, which is adapted to have an up and down movement in the cylinder 5. The plunger 10 has transversely disposed through it, near its upper end, a slot 11, which is adapted to receive the enlarged 70 rounded end 12 of the plunger arm 13. The plunger arm 13 is fixedly secured to the rod 14 by means of the set screw 16. The rod 14 is disposed within the casing 1, and forms 75 an integral part of the lever arm 15, so that upon any movement of the lever arm 15, the plunger arm 13 will move simultaneously 80 with it in the same direction and degree. The inner end of the rod 14 is held in a bearing 85 in the casing 1, and the outer end of the rod 14 is provided with a shoulder 17, which abuts the outer side of the casing 1, and which is held tightly in that position by means of a threaded washer or nut 18 secured to the rod 14 on the inner side of the casing 1. A suitable felt washer 19, and a protective washer 20, are provided around the rod 14 at the outer 90 side of the casing 1 to prevent leakage from the casing, yet at the same time to allow lubrication for the rod 14 where it passes through the casing 1. At the outer end of the lever arm 15 is secured an arm 21 extending from the member 22, which is secured to the axle 23 of the vehicle by any suitable means. The arm 21 is secured to the lever arm 15 and the member 22 by means of a conventional ball and socket joint 24 which does not form a part 95 100

of the invention, and to which no claim is made. The casing 1 is secured to the body of the vehicle by means of the flanges 25 which are formed integrally with the casing 1 and 5 extend therefrom.

The flange 6 of the cylinder 5 is provided at one side thereof with an elongated vertical orifice 26. Positioned below the orifice 26 is a flat valve member 27, mounted on the free 10 end of a spring 28, which is secured to the opposite side of the flange 6. The valve member 27 is of sufficient size and shape to close the orifice 26 when the valve 27 is held in contact with the flange 6 below the orifice 26. The 15 casing 1 is provided near the bottom thereof, with a circular threaded hole which coincides with a hole in the flange 6 of similar size; these holes being adapted to receive the plug valve 29. The plug valve 29 is secured in said 20 hole in such a manner as to allow of slight and partial rotation thereof in the hole. The plug valve 29 has an orifice 30 therethrough in the portion of the plug within the flange, and the flange 6 has a coinciding orifice 31 25 therein. Thus when the orifices 30 and 31 coincide, liquid may flow therethrough, but when the plug has been partially rotated the flow of liquid therethrough will be decreased proportionately. Integrally formed with the 30 plug 29 at a point outside of the casing 1, is an indicator or pointer 32 which coincides with the stops or indicia 33 to indicate on the outside of the casing the relative positions of the orifices 30 and 31. The regulation of the 35 valve 29 is thus simplified by the use of the stops 33 and the pointer 32, as by having one position of the pointer indicate open position of the orifices, as for winter weather, and another position of the pointer indicate partially closed position of the orifices, as for 40 summer weather. The casing 1 is provided at its upper end with an opening 34 through which easy access may be had to the inside of the casing and the parts therein, and which 45 opening is covered with a suitable removable cover 35.

In operation the casing 1 is secured to the chassis or body of the vehicle by the use of suitable fastening means secured through the 50 holes in the flanges 25. The arm 21 is secured, by means of the member 22, to the axle of the vehicle. The casing 1 is filled to a suitable level with an incompressible fluid, such as oil. As the vehicle moves along the road and 55 strikes a bump, the wheels and axle bound upwardly, carrying with them the lever arm 15 and the plunger 10 within the device. The plunger 10, in being pulled upwardly, creates a suction at its under side, and the space within the cylinder 5 and under the plunger 10 is 60 filled with oil which is drawn from the upper part of the device through the orifices 26, 30 and 31. When the plunger has reached the peak of its movement and starts to descend, 65 it is held in check in so doing by the column

of oil in the cylinder. The downward push of the plunger tends to push the oil from within the cylinder, and acts upon the bottom of the valve member 27, pushing it into contact with the bottom of the flange 6, and thereby closes the orifice 26. The oil must then discharge solely through the orifices 30 and 31 which are relatively small, and the plunger is thereby caused to resume its original position slowly, and thus to absorb the shock ordinarily suffered on the rebound.

From the above it will be seen that a shock absorber is provided which is simple of construction and operation, cheap of manufacture, easy to assemble, accessible for repairs, and adjustable for varying weather conditions.

The invention having been set forth, what is claimed as new and useful is:—

1. A shock absorber comprising a fluid 85 containing casing, a cylinder detachably secured in said casing in spaced relation thereto, a recessed flange carried by the upper end of said cylinder and adapted to abut a shoulder on the inner side of said casing, a plunger disposed in said cylinder, a lever arm, and a plunger actuated by said lever arm, said plunger arm having a free bearing connection with said plunger.

2. A shock absorber comprising a fluid 95 containing casing, a cylinder disposed in said casing having laterally extending flanges forming a partition between the upper and lower parts of the casing, a piston operable in said cylinder, means controlling the piston 100 movement, means whereby fluid is quickly drawn into the cylinder upon a stroke of the piston in one direction, and means carried by one of said flanges whereby the discharge of fluid from the cylinder is restricted on the 105 return stroke of the piston.

3. A shock absorber comprising a fluid containing casing, an annular angular shoulder carried by the inner side of said casing, a cylinder detachably disposed in said casing, a recessed bevelled flange carried by the upper end of said cylinder and abutting said shoulder, an annular flange carried by said cylinder having a threaded portion cooperating with a threaded portion of said casing to hold the cylinder to place, a detachable closure carried by the open end of said casing, a plunger operating in said cylinder, and valves carried by the annular flange.

4. A shock absorber comprising a fluid containing casing, a cylinder disposed in said casing, a plunger operating in said cylinder, a flange carried by said cylinder and secured to said casing, valves disposed in said flange, means whereby one of said valves may be regulated from the outside of the casing, and means cooperating with said regulating means for indicating the degree of regulation of said valve.

5. A shock absorber comprising a fluid con-

- taining casing, a cylinder having a laterally extending flange forming a partition between the upper and lower part of the casing, a check valve carried by said flange, said flange having a port formed therein, an adjustable valve member cooperating with said port and extending without the casing, a plunger operable within the cylinder, and means controlling the plunger movement.
- 5 6. A shock absorber comprising a fluid containing casing, a cylinder having a laterally extending flange forming a partition between the upper and lower part of the casing, a check valve carried by said flange, said flange having a port formed therein, an adjustable valve member cooperating with said port and extending without the casing, means indicating the degree of adjustment of said valve member, a plunger operable within the cylinder, and means controlling the plunger movement.
